UNITED STATES PATENT OFFICE.

PAUL P. I. FYFE, OF CONCORD, NORTH CAROLINA, ASSIGNOR OF TWO-FIFTHS TO THE CLEAVERS CLUB & MANUFACTURING COMPANY, OF SAME PLACE.

DEVICE FOR CONTROLLING FLOW OF WATER IN PIPES.

SPECIFICATION forming part of Letters Patent No. 673,165, dated April 30, 1901.

Application filed November 16, 1900. Serial No. 36,753. (No model.)

To all whom it may concern:

Be it known that I, PAUL P. I. FYFE, a citizen of the United States, and a resident of Concord, in the county of Cabarrus and State 5 of North Carolina, have invented a new and Improved Device for Controlling the Flow of Water in Pipes, of which the following is a full, clear, and exact description.

One purpose of the invention is to provide 10 such a connection between the water-supply and water-service pipes that the water may quickly flow from one to the other or whereby the connection between the pipes may be cut off any length of time, during which time 15 all the house-pipes will be empty of water and the water thus freed conducted to the sewer or other drain.

A further purpose of the invention is to accomplish the above-named results through 20 the medium of a single slide-valve operated within the building.

The invention consists in the novel construction and combination of the several parts, as will be hereinafter fully set forth, 25 and pointed out in the claims.

Reference is to be had to the accompanying drawing, forming a part of this specification, in which is represented a vertical section through a part of the lower portion of a building 30 and adjacent ground and a partial side elevation and partial sectional view of the improved device.

A represents the cellar or lower portion of a building; B, the water-main; C, the sewer or other drain; D, the water-supply pipe connected with the main and which extends within the apartment A, and E a portion of the service-pipe for the building. These two pipes D and E are connected by a valve-casing F, 40 and in this valve-casing a plug 10 has sliding movement, the plug being provided with an opening 11, extending through from side to side and which in one position of the plug connects with both the water-supply pipe D and the service-pipe E. The valve-plug 10 is further provided with an angular opening or port 12, and this angular port or opening extends through one side only of the plug—that side which faces the service-pipe E—and 50 the vertical portion of the angular opening

or port 12 extends out through the bottom of the said plug.

A hub 13 is attached to the bottom portion of the casing, both the top and bottom of the casing being open where the plug 10 has movement, and this hub 13 may constitute a portion of a drain-pipe 14, and such pipe is usually carried to the sewer or other convenient conduit.

The plug 10 is shown operated through the medium of a lever 15, which is fulcrumed upon a suitable support 16, located within the lower apartment A of the building, and one end of this lever 15 has a link and pivotal connection 17 with the upper portion of the valve-plug 10, while a spring 18 may be attached to the opposite end of the said lever 15 and to any support. This spring 18 may be so arranged that it will normally hold either one of the two ports in the valve-plug 70 in position for service; but the spring 18 may be omitted and the lever 15 may be operated by hand.

In operation when water is to be supplied from the main B to the service-pipe E the valve-plug 10 is lowered and the upper or through port 11 is placed in communication with the pipe leading from the main to the near-by service-pipe. Should it be thought that the water in the service-pipe might freeze 80 during the cold weather, the water may be temporarily shut off from the main B by carrying the through-port 11 to the upper portion of the valve-casing and bringing the angular port 12 in communication with the service-pipe connected with the valve-casing, whereupon water will be cut off from the supply-pipe to the valve and its casing; but all the water contained in the house-pipes will escape through the angular outlet-port 12 and 90 through the medium of the branch drain-pipe 14 to the sewer.

Having thus described my invention, I claim as new and desire to secure by Letters Patent—

1. In a device for controlling the flow of water in pipes, a supply-pipe, a service-pipe, a valve-casing connecting the two pipes, a plug mounted to slide in said valve-casing and provided with a port extending through from side 100

to side and adapted to register with both the supply and service pipes, and a second port extending through one side of the plug only and out through the bottom portion thereof 5 one member of said latter port being adapted to be brought into registry with the service-pipe, and a lever fulcrumed upon a suitable support and connected at one end with one end of the valve-plug, whereby said ports 10 may be brought into operation, as described. 2. In a device for controlling the flow of water in pipes, the combination, with a source of water-supply, a pipe leading from the said source, a service-pipe, and a valve-casing connecting the two pipes, said valve-casing having a central opening extending through from top to bottom, and which is in communication with both of said pipes, of a plug held to slide in the said central opening of the valve-casing, the plug extending through and beyond the valve-casing at the top and at the bottom, the said plug being provided with a through-port extending from one side to the other and adapted to register with both of the said pipes, 15 and a second angular port which extends from one side and out through the bottom of the 20

plug, the angular port being adapted for registry with the service-pipe only, an offtake, a connection between the lower portion of said valve-casing and said offtake, a lever, 30 and a link connection between said lever and the said valve-plug, for the purpose described.

3. The combination with a water-supply pipe, and the service-pipe, of a valve-casing connecting the two, a plug mounted to slide in said casing and provided with a port adapted to register with both the supply and service pipes, and a second port adapted to connect the service-pipe with an offtake leading from the valve-casing, a lever fulcrumed on a suitable support, a connection between one end of the said lever and the valve-plug, and a spring connected with the other end of said lever and with a support, for the purpose set forth. 40

In testimony whereof I have signed my name to this specification in the presence of two subscribing witnesses.

PAUL P. I. FYFE.
